ELECTRICAL CONTROLS CABINET

William H. Wood, Roanoke, and Heinrich W. Huber,
Salem, Va., assignors to General Electric Company,
a corporation of New York

Filed Oct. 24, 1966, Ser. No. 4,412

Term of patent 14 years

(Cl. D26—5)

The figure is a perspective view taken from the front and right side of an electrical controls cabinet embodying our new design, the left side being essentially the same as the right side and the rear is substantially plain.

We claim:

The ornamental design of an electrical controls cabinet, as shown and described.
